UNITED STATES PATENT OFFICE.

HERBERT R. SIMONDS, OF DAYTON, OHIO.

BED-PLATE FOR PAPER AND RAG ENGINES.

SPECIFICATION forming part of Letters Patent No. 771,582, dated October 4, 1904.

Application filed April 24, 1903. Serial No. 154,173. (No model.)

To all whom it may concern:

Be it known that I, HERBERT R. SIMONDS, a citizen of the United States, residing at Dayton, in the county of Montgomery and State 5 of Ohio, have invented certain new and useful Improvements in Bed-Plates for Paper and Rag Engines; and I do hereby declare the following to be a full, clear, and exact description of the invention, such as will enable others 10 skilled in the art to which it appertains to make and use the same.

My invention relates to that class of bed-plates in which the blades are so arranged as to form several series of diamond - shaped 15 knives; and it has for its special object to provide means whereby this result may be obtained without the use of the old dovetailing feature, which in practice has been found to weaken the blades.

20 My invention consists in the novel construction fully and clearly described and illustrated in the accompanying specification and drawings.

In the drawings, Figure 1 is a top plan view 25 of my improved bed-plate. Fig. 2 is a perspective view of one of the blades employed in my device.

A in the drawings represents a frame of suitable shape, size, and material adapted to 30 inclose a series of blades B, bent into a zig-zag form and so arranged that the external angles of adjacent blades are in contact with each other, thus forming a series of diamond-shaped recesses between each pair of blades, 35 the construction of the blades being such that a perpendicular line xx dropped from one of the sides of the frame will pass through but one of the points of contact of the blades.

C C are blocks, preferably of wood, adapted to fit into said diamond-shaped recesses and 40 also in the recesses formed between the blades and said frame A to prevent all chance of the blades slipping. D D D are bolts provided with nuts D' D', passing through said frame, 45 blades, and blocks and adapted to hold the same rigidly together. In the drawings the apexes of the exterior angles of the blades have been illustrated as being pointed; but, if desirable, they may be flattened to insure greater rigidity. Hence it is evident that 50 this construction will have all the qualities of the old dovetailed plate with the advantage of being much stronger and durable.

What I claim, and desire to secure by Letters Patent, is—

The herein-described diamond bed-plate for paper and rag engines, comprising among its members, a plurality of separate blades bent into zigzag form and arranged with the external angles of adjacent plates in contact with 60 each other, whereby two series of substantially continuous parallel cutting edges are provided, the cutting edges of one series crossing those of the other series angularly, the construction of said blades being such that 65 not more than one of the points of contact of the plates will be in a perpendicular line dropped from one side of the frame, substantially as described.

In testimony whereof I affix my signature in 70 the presence of two witnesses.

HERBERT R. SIMONDS.
